UNITED STATES PATENT OFFICE.

JOHANN SCHÜTTE, OF LANGFUHR, NEAR DANZIG, GERMANY,

BALLOON STRUCTURE.

988,597.

Specification of Letters Patent.

Patented Apr. 4, 1911.

Application filed July 12, 1909. Serial No. 507,147.

To all whom it may concern:

Be it known that I, JOHANN SCHÜTTE, a subject of the King of Prussia, residing at 47b Jäschkenthalerweg, Langfuhr, near Danzig, Germany, have invented certain new and useful Improvements in Balloon Structures; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 My invention relates to a balloon construction for air ships and has for its object the construction of such a balloon from a number of independent inflatable elements, and more especially of a number of spherical 20 balloon elements having interposed between them inflatable rings of triangular, elliptical or circular cross section interposed between spherical balloons and designed to fill the spaces between them, the entire structure being assembled within a stiffened hull 25 or cover.

30 Referring to the drawings in which like parts are similarly designated, Figure 1 is a vertical longitudinal central section of a balloon made in accordance with my invention. Fig. 2 is a section taken on the line $x-y$ of Fig. 1. Fig. 3 is an enlarged partial transverse section of one-half of a balloon. Fig. 4 is an enlarged longitudinal 35 section showing a portion of two balloon elements. Fig. 5 is a detail partial cross-sectional view, on a larger scale, of the outer casing and the tension bands and Fig. 6 is a detail partial longitudinal section of the parts shown in Fig. 5.

40 The inflatable elements of the balloon are contained within an outer casing having a double wall comprising an outer wall H' and an inner wall H'' stretched respectively over and under longitudinal strips or carriers L of aluminium, wood or thin steel, corresponding in shape to the curvature of the balloon casing and mounted edgewise thereto, (Figs. 5 and 6) thereby maintaining the inner and outer wall H'' and H' of the casing spaced from one another to form an inclosing casing for the inflatable elements containing between its inner and outer layer an air space, which air space serves as an insulating medium for protecting the inflatable elements contained within the casing

from external temperature influences. The casing so formed contains a number of inflatable elements preferably but not necessarily, independent of one another and here shown as spherical balloons B varying in diameter in accordance with the shape of the casing surrounding them and between these balloon elements B and the casing are a number of inflatable ring like elements B' of suitable cross section, corresponding to the shape of the space R here shown as substantially triangular in section. These ring elements may be of any other desired geometrical shape in section as for example, elliptical or circular. The longitudinal ribs 50 L are mounted on transverse rings G' , G'' ... G^{12} (Figs. 3 and 4) which are perpendicular to the longitudinal axis of the entire balloon. These circular ribs G' to G^{12} are reinforced preferably by tension bands S and S' . To the longitudinal carriers L eyes O are mounted. To the latter the tension bands S are attached, which connect with ring shaped pipe U embracing the same and leading to another eye O again in the manner shown in Figs. 5 and 6. The ring U surrounds the contact point of adjoining inflatable spherical members B in such a manner that the bands S are tangent to the inflatable balloon element B contained within them. Other lacings S' cross one another and connect the rings G' G'' ... G^{12} after the manner of triangular lattice work as clearly indicated in Fig. 1 also tangent to the surface of the inclosed inflatable balloon element B . The several rings G together with their lattice like interconnecting bands form connected frame work or pockets for the spherical inflatable elements, each pocket being composed of two or more lattice-like conefrusta shaped elements.

95 I claim:

1. A balloon for air ships comprising a casing, a plurality of spherical inflatable balloon elements contained therein and inflatable annular elements interposed between adjoining spherical elements and the casing.
2. The combination with an outer casing, a plurality of spherical inflatable balloon elements contained therein and an auxiliary lattice casing for each inflatable spherical balloon element.
3. The combination with an outer casing a plurality of spherical inflatable balloon elements contained therein, an auxiliary lattice casing for each inflatable spherical bal-

loon element, and each lattice casing composed of a plurality of cone frusta shaped elements.

4. The combination with an outer casing; 5 of a plurality of spherical inflatable balloon elements contained therein and an auxiliary latticed casing for each element and connected to the casing, said lattice casing formed of an assemblage of cone-frusta shaped elements thereby forming annular spaces between the casing and said frusta at the contact points of the spherical elements, and annular inflatable elements contained in said spaces.

15 5. The combination with an outer casing

comprising an inner and an outer wall spaced apart by longitudinal I-shaped stiffening members, of a plurality of inflatable spherical balloon elements contained in said casing, and an auxiliary latticed casing for 20 each element attached to said stiffening members.

In testimony that I claim the foregoing as my invention, I have signed my name in presence of two subscribing witnesses.

JOHANN SCHÜTTE.
